(57) **CLAIM**

The ornamental design for a spirit level and components thereof, substantially as shown and described.

DESCRIPTION

FIG. 1 is a front perspective view of a spirit level including a main body, a central horizontal bubble vial housing, a left side handgrip and a right side handgrip, a left side vertical bubble vial housing and a right side vertical bubble vial housing, a left side end cap and a right side end cap;

FIG. 2 is a front elevation view of the spirit level of FIG. 1; FIG. 3 is a right side elevation view of the spirit level of FIG. 1;

FIG. 4 is a top elevation view of the spirit level of FIG. 1; FIG. 5 is a bottom elevation view of the spirit level of FIG. 1; FIG. 6 is a rear elevation view of the spirit level of FIG. 1; FIG. 7 is a left side elevation view of the spirit level of FIG. 1; FIG. 8 is a close up front perspective view of the left side end cap of the spirit level of FIG. 1;

FIG. 9 is a close up front elevation view of the end cap of FIG. 8;

FIG. 10 is a close up front perspective view of a hand grip of the spirit level of FIG. 1;

FIG. 11 is a close up front elevation view of the handgrip of FIG. 10;

FIG. 12 is a close up perspective view of a vertical bubble vial housing of the spirit level of FIG. 1; and,

FIG. 13 is a close up front elevation view of the vertical bubble vial housing of FIG. 1.

The broken lines along the main body of the spirit level in FIGS. 1, 2, 4, 5 and 6 indicate that the lengths between the horizontal bubble vial housing and its adjacent handgrips, a vertical bubble vial housing and its adjacent handgrip, and an end cap and its adjacent vertical bubble vial housing can vary from the size as shown in FIG. 1 without the broken lines to larger sizes in which only that part of the main body is elongated; the broken lines form no part of the claimed design.
